DAVID B. GALBALLY, OF NEW YORK, N. Y., ASSIGNOR, BY MESNE ASSIGNMENTS, TO THE STEEL PACKAGE COMPANY, OF WASHINGTON, DISTRICT OF COLUMBIA, A CORPORATION.

METALLIC BARREL.

1,054,106.

Specification of Letters Patent. Patented Feb. 25, 1913.

Application filed June 24, 1912. Serial No. 705,632.

To all whom it may concern:

Be it known that I, DAVID B. GALBALLY, a citizen of the United States, residing at New York, in the county of New York and 5 State of New York, have invented certain new and useful Improvements in Metallic Barrels; and I do hereby declare the following to be a full, clear, and exact description of the invention, such as will enable others 10 skilled in the art to which it appertains to make and use the same.

This invention relates to metallic barrels, and has for its object to produce such barrels from individual staves, while firmly 15 locking them together in a more efficient and less costly manner than has heretofore been practical.

To these ends the invention consists in the novel combinations of parts and details 20 of construction more fully hereinafter disclosed and particularly pointed out in the claims.

Referring to the accompanying drawings forming a part of this specification, in which 25 like numerals designate like parts in all the views: Figure 1 is a diagrammatic view, illustrating a pair of flat staves placed edge to edge preparatory to being curved to shape. Fig. 2 is a view similar to Fig. 30 1, illustrating the operation of forcing the locking strip over the meeting edges of the staves in order to bind them together and simultaneously curve them to shape. Fig. 3 is an enlarged sectional view, in perspective, of the joint formed between the staves. Fig. 4 is a view similar to Fig. 3, but illustrating the flanged head portion of the barrel. Fig. 5 is a top plan view of the barrel, 35 without the top; and Fig. 6 is a longitudinal 40 sectional view of a completed barrel employing my joint.

1 indicates flat staves cut from flat metal sheets by any suitable means. These staves are provided along their ends with the off- 45 set flanges 2, providing the seats 3 for the head 4, and have along their longitudinal edges the locking flanges formed by turning up said edges, by any suitable means, so that each, when in the position shown in

Fig. 3, will be composed of a vertical member 5, a horizontal member 6, a second vertical member 7 and a second horizontal member 8.

In order to firmly lock the flanges of two adjacent staves together, I provide the locking strip 22, formed from a single flat piece of metal so bent upon itself that one edge, when in the position illustrated in Fig. 3, forms the horizontal member 9, fitting between the body 1 of the staves and the first 55 horizontal member 6 of its locking flange. Said locking strip 22 is further so bent as to provide the vertical member 10 extending at right angles to the member 9, and extending parallel to the member 7 of the locking 60 flange when in contact therewith. The said locking strip is further bent so as to provide the second horizontal member 11, extending at right angles to the member 10, and bent again at right angles to the said second 65 horizontal member 11 to form the second vertical member 12, and then bent at right angles to the said second vertical member 12 to form the third horizontal member 13. After being bent at right angles to form the 70 third horizontal member 13, as above described, the material of the said locking strip 22 is next bent flat back upon itself to form the fourth horizontal member 14, which extends twice the length of the said 75 third member 13, whereupon it is again bent flat upon itself to form a fifth horizontal member 15, and then at right angles to the member 15 to form a third vertical member 16. From the member 16 the material of 80 the locking strip 22 extends at right angles to form the sixth horizontal member 17, and then at right angles to the member 17 to form the fourth vertical member 18, and finally at right angles to the member 18 to 85 90 form the seventh horizontal member 19, which constitutes the other edge of the said locking strip 22.

In forming the locking flanges on the staves 1, the first vertical members 5 are 95 made of a length just sufficient to cause the first horizontal members 6 to be located a distance away from the body of the stave 1

to form recesses for the snug accommodation of the horizontal members 9 and 19 of the locking strip 22, while the spaces left on said locking flanges between the horizontal members 6 and 8 are just sufficient to snugly accommodate the parallel bent members 13 and 14, and 14 and 15, respectively, of the locking strip. Further the vertical members 12 and 16 of the locking strip 10 are chosen of proper dimensions to afford recesses adapted to snugly accommodate the horizontal members 8 of the locking flanges. It results from the structure just disclosed that when the parts are in the positions indicated in Fig. 3, each member of the locking flanges is inclosed by one or more members of the locking strip 22, and that while the vertical members 5 of two adjacent flanges are brought into contact to form a 15 tight joint at 20, the members 13, 14 and 15 constitute a firm brace or stiffening rib which causes said joint to effectually resist strains of all kinds that may be brought upon the finished barrel. Further it will be 20 observed that the staves 1 are cut out of flat material with curved edges, as shown. It therefore follows that if their curved edges are brought together as illustrated in 25 Fig. 1, the said edges cannot meet in the plane indicated by the dotted line 21, unless the bodies of said staves are curved into a concavo-convex shape. But it is further evident, on the other hand, that if the said edges are brought together, as illustrated in 30 Fig. 2, and the locking strip 22 driven or otherwise forced into the position as shown in Figs. 3 to 6, then the curved edges of said flat staves 1 will be forced to meet in a plane such as 21, and the body portions 35 of said staves will thereupon be forced to assume a concavo-convex shape as a result of said driving action. Further the flexing of the stave bodies, in the manner indicated, results in a wedging action between the 40 parts, as well as in a setting up of stresses 45 in the metal, causing the interlocking members of the stave flanges and locking strip to be put under a tension. It follows, as a result of the complex tensioning strains 50 thus set up, that a joint 20 of extraordinary tightness and stability is produced. In addition to the above, this joint or seam 20, is bridged by the tightly fitting, longitudinally curved, bracing member 14, which further insures against leakage.

The entire construction offers no edges which can be broken by bending or twisting while rolling the barrel, and it is found in 55 practice to be the strongest part of the barrel. The locking pieces 22, after being driven home, are cut off even with the seats 3, at each end of the barrel, and their ends 60 form additional supports for the heads 4.

It will also be observed that the longitudinally curved members 14 of the locking pieces 22, which bridge the seam 20, being located on the inside of the transversely and longitudinally curved staves, acts somewhat like the keystone of an arch, and prevents the staves from shifting after the hoops 24 70 are put on.

It is obvious that those skilled in the art may vary the details of construction without departing from the spirit of my invention, and therefore I do not wish to be limited to the above disclosure except as may be required by the claims.

What I claim is:

1. In a metallic barrel provided with a bilge, the combination of a plurality of 80 longitudinally and transversely curved staves, each provided on their longitudinal edges with locking flanges comprising two horizontal and two vertical members forming recesses opening in opposite directions; 85 with a locking strip with horizontal members adapted, when two opposing flanges are brought into contact, to snugly fit each of said open recesses and to firmly bind the said flanges together, substantially as described.

2. In a metallic bilge barrel, the combination of a plurality of curved staves each provided on each longitudinal edge with a locking flange, each flange having an outer 95 recess opening toward the body of the stave, and an inner recess larger than said outer recess opening in an opposite direction, the said inner recesses of two opposing meeting flanges forming a single enlarged inner recess with a central radial opening; with a locking strip surrounding said meeting locking flanges having opposing edges entering the said outer recesses of said flanges, and having a bracing member fitting the 100 105 said enlarged inner recess of the opposing flanges, substantially as described.

3. In a metallic bilge barrel, the combination of a plurality of curved staves each provided on its longitudinal edges with 110 locking flanges, each flange having outer and inner locking recesses opening in opposite directions; with a locking strip having edge members fitting the said outer recesses of two opposed locking flanges, and having a 115 stiffening intermediate rib member fitting the said inner locking recesses of the said two flanges while extending across and sealing the seam formed by the contacting edges of said flanges, substantially as described.

4. In a metallic bilge barrel, the combination of a plurality of curved staves each provided on its ends with an offset flange forming a seat for the head of the barrel 125 and on its longitudinal edges with locking

flanges, each flange having outer and inner locking recesses opening in opposite directions; with a locking strip having edge members fitting the said outer recesses of

5 two opposed locking flanges, and having a stiffening intermediate rib member fitting the said inner locking recesses of the said two flanges while extending across and seal-

ing the seam formed by the contacting edges of said flanges, substantially as described. 10

In testimony whereof, I affix my signature, in presence of two witnesses.

DAVID B. GALBALLY.
